UNITED STATES PATENT OFFICE.

MANNING M. ROUSE, OF CORRY, PENNSYLVANIA.

PROPPED LADDER.

No. 806,501.

Specification of Letters Patent.

Patented Dec. 5, 1905.

Application filed April 27, 1905. Serial No. 257,568.

To all whom it may concern:

Be it known that I, MANNING M. ROUSE, a citizen of the United States, residing at Corry, in the county of Erie and State of Pennsylvania, have invented certain new and useful Improvements in Propped Ladders, of which the following is a specification, reference being had therein to the accompanying drawings.

10 My invention relates to extension-ladders, and more particularly to that class known as "step-ladders," one of the objects of the invention being to provide a device of the character described that shall be simple and inexpensive in construction, durable, and effective in operation.

20 A further object of the invention is to provide an extension step-ladder having adjustable braces by means of which the props may be regulated and by means of which the ladder may be set against a wall while the props are held rigidly in position, thus avoiding the danger of slipping.

25 Other objects and advantages of my invention, as well as the structural features by means of which these objects are attained, will be made clear by an examination of the specification, taken in connection with the accompanying drawings, in which the same reference-numerals indicate corresponding portions throughout, and in which—

30 Figure 1 is a perspective view of my ladder, showing the slidably-mounted section lowered. Fig. 2 is a perspective view showing the slidably-mounted section raised. Fig. 3 is a transverse section through the front props. Fig. 4 is a transverse section through the rear props. Fig. 5 is a detail perspective of a portion of the adjustable 35 brace, and Fig. 6 is a detail perspective of a portion of the other brace.

1 designates a section of a step-ladder constructed in the ordinary manner, with longitudinal plates 2 secured to the front edges of the side bars and having tongues 3 formed on the back edges of said bars and adapted to rest in grooves 4 in the front edges of a ladder-section 5, adjustably and slidably mounted on said section 1 by means of the tongues 45 and grooves 3 and 4 and also by means of clamps 6 of a well-known construction, which are rigidly fixed on the slidable section 5 near its lower end, each one being provided with a set-screw 7 in the front part 50 thereof, by means of which said section 5 is

secured rigidly in place when raised or lowered.

7 designates a prop-section having longitudinal plates 4 secured to the outer edges of each prop, each prop being provided with a 60 groove 9, and 10 designates an extension-section adjustably mounted on the section 7 by means of longitudinal tongues 11, traveling in the grooves 9, and also by means of supporting-clips 12, rigidly secured to the prop-section 7. The extension-section 11 has rigidly mounted thereon clips 13 of the ordinary construction, with set-screws 14 engaging with the longitudinal plates 8, by means of which the extension-section 11 is secured in 70 position when raised or lowered.

15 The extension 5 has rigidly secured at its upper end the supporting-plates 15, carrying a platform 16, the upper ends of each prop of the extension-section 11 being pivotally 75 mounted on the plate 15.

17 designates a brace between the ladder-sections, said brace comprising two arms 18, one of said arms carrying a lateral projection 19 at one end and the other arm having slots 80 or grooves 20 therein. The two arms are pivotally connected, as shown at 21, one of said arms having pivotally mounted thereon a link 22, which is provided with a lateral projection 23 at its end, said lateral projection being adapted to engage with the grooves or notches 20, thus affording means by which the braces are adjusted.

24 designates another folding brace comprising two arms, one of which is pivoted on 90 the front and the other on the rear prop. One of said arms is provided with a lateral projection 25, which engages with a kerf 26 in the other arm, whereby the two arms are braced to aid in holding the props in position 95 when the ladder is being used.

25 From the foregoing description of my invention it will be observed that my ladder is constructed in two sections—namely, an upper and a lower—and in operation, where a 100 higher elevation than that attainable by the ordinary ladder is desired to be reached, the upper section is extended, as best shown in Fig. 2, and held in position by means of the clamps 6 and 13 and the set-screws 7 and 14 105 in conjunction therewith.

Two particularly useful features are possessed by my ladder, one being the extension feature, enabling a person to adjust the ladder to reach heights not attained by the ordi- 110

- nary and well-known construction of step-ladder, and the other being the manner of bracing the props. It will be observed that by my method the props may be placed 5 astride any desirable distance, this arrangement of parts being particularly useful where it is desired to utilize a step-ladder against a wall. By means of the arms 18, the lateral lugs 19 and 23, and the grooves 20 one or 10 both of the braces 17 may be adjusted to permit the rear props to stand in a perfectly vertical position while the step-carrying props are arranged at an angle enabling a person to conveniently ascend or descend the same. 15 Having thus described my said invention, what I claim as new, and desire to secure by Letters Patent of the United States, is—
1. A propped ladder - brace comprising arms pivotally mounted on the ladder and 20 also pivotally connected with each other, one of said arms carrying a lateral projection at its outer end, and a link pivoted on said arm and having a lateral projection adapted to engage with notches or kerfs in the other arm 25 whereby the two arms are held in braced position, substantially as described.
2. In a stepped and propped ladder, the combination, with slidably-mounted sections, of a tongue-and-groove connection between 30 said sections, longitudinal plates carried by one section, a plurality of clamps and set-screws carried by the other section, the set-screws being arranged to engage with the plates whereby the extension-section is held

in adjusted and operative position, arms pivotally mounted on the sections and also pivotally connected with each other, one of said arms carrying a lateral projection at its outer end, and a link pivoted on said arm and carrying a lateral projection adapted to engage with notches or kerfs in the other arm whereby the two arms are held in braced position, substantially as described. 35

3. In a stepped and propped ladder, the combination, with slidably and adjustably mounted inner and outer sections, of tongue-and-groove connections between said sections, longitudinal plates mounted on each outer section, set-screws rigidly mounted on the inner section and adapted to engage with the plates on the outer section to hold said sections in adjusted position, clamps rigidly mounted on the inner section and carrying the set-screws, clamps rigidly mounted on one of the outer sections to aid in connecting 50 the two sections together, and braces connecting said sections, one of said braces being comprised of pivotally-mounted arms, one of which is provided with a pivoted lateral projection adapted to engage in a kerf in the opposite arm, substantially as described. 55

In testimony whereof I hereunto affix my signature in presence of two witnesses.

MANNING M. ROUSE.
